CLAIM

The ornamental design for a stopper for bottle, as shown and described.

DESCRIPTION

FIG. 1 is a top perspective view of a stopper for bottle showing our new design;

FIG. 2 is a bottom perspective view thereof;

FIG. 3 is a left side view thereof, the right side being a mirror image thereof; and,

FIG. 4 is a front view thereof, the rear view being a mirror image thereof.

The broken lines are shown for the purpose of illustrating parts of the stopper for bottle that form no part of the claimed design.
